PLACER WASHING APPARATUS

Henry G. Martin, Diablo Heights, C. Z.

Application December 5, 1941, Serial No. 421,782

1 Claim. (Cl. 209—451)

This invention relates generally to apparatus for separating solids having different specific gravities. It is more particularly directed to a machine in which placer gold or platinum containing sands and gravels or free gold in crushed rock may be treated to separate the precious metals from the less valuable mineral matter.

An object of the invention is to provide a gold washing machine with a rotating drum element having riffle-forming means on its exterior peripheral surface and means for moving the element whereby the riffles will pass the discharge end of a chute or similar device utilized to convey previously screened sands or gravels to the machine, means also being provided to supply the riffles with water which flows over the riffles in a direction opposed to their movement whereby the lighter unwanted solids will be conveyed toward the waste discharge while the desired materials are retained in the riffles and conveyed thereby to the point of removal, means being provided to effect positive removal thereof in the event the same do not voluntarily separate therefrom.

Other objects will be apparent from the following description and the accompanying drawings, in which a washing apparatus formed in accordance with the present invention has been disclosed in detail.

In the drawings:

Fig. 1 is a perspective view of the washing apparatus;

Fig. 2 is a detail vertical sectional view taken through the apparatus and illustrating the movable riffle carrying element thereof;

Fig. 3 is a detail vertical sectional view taken on the plane indicated by the line III—III of Fig. 2.

Referring more particularly to the drawings, the numeral 1 designates the washing apparatus in its entirety. In this instance, the apparatus includes a substantially rectangular open frame 2 which is formed from a plurality of vertically and horizontally extending angle bars 3 and 4, respectively, suitably joined to form a unit having bottom, center and top rails. At their intermediate portions, the center rails are provided with bearing blocks 5 for the reception of the ends of an axle 6. The axle may be rotatably supported within the bearing blocks for the movable support of a drum 7.

The drum may be formed from any suitable material capable of withstanding the uses to which the apparatus will be placed and preferably from an inexpensive material which will be

unaffected by moisture. The drum includes end walls 8 and a cylindrical peripheral wall 9. To this latter wall, there is secured an outer covering 10 which is transversely grooved to provide a series of alternately arranged high and low portions in the nature of corrugations. The covering 10 may be formed of sheet metal or it may be an integral part of the peripheral wall 9. The side walls 8 extend outwardly beyond the covering 10 to provide flanges at the ends of the corrugations to prevent the escape of water therefrom. Due to the shape of the drum and the manner of mounting the same in the frame, the drum will be free to revolve about a horizontal axis whereby the riffles will be consecutively presented to the discharge end of a chute 11 over which materials to be separated may pass in the operation of feeding the machine.

To effect the rotation of the drum, it is provided with a groove 12 for the reception of an endless belt 13 also trained around a small pulley 14 carried by a shaft 15. This shaft is journaled in bearings 16 carried by a plate 17 supported on the bottom rails of the frame adjacent to one end thereof. A secondary pulley 18 is provided on this shaft to receive a second endless belt 19 employed in transmitting rotary motion from a power driven pulley 20. To drive the pulley 20, there is provided a small internal combustion engine 21, this member being mounted on a supporting shelf 22 positioned on the center rails substantially in vertical registration with the plate 17. Suitable control means, not shown, may be provided to disconnect the pulley 20 from the driving shaft 35 of the engine when it is desired to interrupt the rotation of the drum and yet keep the engine in operation.

Rotation of the shaft 15 also serves to operate a pump 23 employed to elevate water from a primary reservoir 24 to a secondary reservoir 25. A pipe line 26 extends from the reservoir 24 to the pump 23 and a second pipe 27 extends from the pump to the reservoir 25. The outlet of the latter reservoir communicates with a valved line 28 which leads to a ported spray head 29. This head is of tubular form and extends transversely of the frame immediately above the drum 7. The head 29 and the ports therein are so arranged that streams of water will be discharged onto the corrugated cover 10 slightly in advance of a vertical plane passing through the longitudinal axis of the drum shaft. When the drum is driven by the engine, it will rotate in a counterclockwise direction as viewed in Figs. 1 and 2. The drum rotates at a relatively slow rate so that the water

issuing from the head will flow over the riffles in a clockwise direction even though the drum is rotating toward the head.

When the materials to be separated are discharged from the chute 11, they will be deposited in the stream of water flowing over the riffled surface. If the materials contain soil, it will be softened and carried away by the water. The lighter solids such as small sand and gravel will also be carried away or moved in a clockwise direction over the surface 10 to a discharge chute 30 supported by the framework in a plane below the center of the drum. The receiving end of the chute 30 is located in close relation to the periphery of the drum to catch the water and waste materials as they fall from the surface of the drum after they have reached a point in horizontal registration with the axis of rotation. Due to the corrugations or riffles, the solid materials will be agitated and washed, whereby the heavier particles will be caused to separate from the lighter undesired materials. These heavier particles will settle in the lower portions of the corrugations and move with the drum in opposition to the direction of flow of the stream of water. The continued rotation of the drum will carry these heavy particles to a collector 31 mounted in the frame below the drum. The member 31 is arcuate in form and extends partly around the lower portion of the drum to catch the particles as they fall from the corrugations under the influence of gravity. In the event all of the particles do not drop from the drum, they will be positively removed therefrom by a scraper element 32 mounted at one end of the collector 31. Other means, such as a jet of water, may be substituted for or used in conjunction with the scraper element to effect the removal of the material adhering to the drum.

The scraper may be formed from a resilient material, if desired, to more closely engage the cover 10. It may be resiliently held in engagement with the cover by a leaf spring 33 which is secured to the member 31 and engaged with lugs 34 carried by brace members 35 forming part of the frame. The spring 33 yieldably maintains the scraper in engagement with the corrugated cover and permits it to move over the elevated portions thereof as the drum revolves. The materials collected by the member 31 will gravitate to a sump 36 provided at its lowermost portion. This sump communicates with a tube 37, the discharge end of which registers with a receiver 38. Through the provision of the scraper, very fine sediment will be removed from the surface of the drum, thus preventing this material from being carried around to the point where it could possibly be removed by the fresh charges of materials to be separated.

Untreated materials may be supplied to the machine by introducing them to a coarse screen 39 supported in an inclined position over a chute 40. This chute is also inclined and is supported above the drum by legs 41. The coarse gravel is removed by the screen and will roll down this 65

member to a chute 42 provided for receiving and conducting the coarse waste to a point of storage. The finer gravel and gold-containing material will gravitate along the chute 40 and be discharged from the lower end thereof onto the chute 11 over which it travels to the drum to be separated in the manner above described. The water is separated from the waste for recirculation by providing the chute 30 with a fine screen 43 in vertical registration with the reservoir 24. As the waste and water flow along the chute 30, the water will pass through the screen 43 and into the reservoir 24 from which it will be moved by the pump 23 to the reservoir 25. The flow of water to the drum is controlled by a valve 44 positioned in the line 28.

The separation of the materials during the washing is facilitated by providing one of the bearings 5 with a ratchet-like surface 45 disposed for engagement with a similar surface formed on a hub 46 of the drum. The ratchet-like surfaces are held in yieldable engagement by positioning a coil spring 47 between the other bearing and the second hub of the drum. As the drum is revolved, it will be caused to vibrate horizontally and impart a shaking action to the materials being separated.

While apparatus has been proposed heretofore which embodied the use of riffled surfaces and rotating drums, it is believed that the combination of these elements and the location of the riffles on the exterior of the rotating drum will provide a highly efficient mechanism for separating solids. While the arrangement of the other elements of the combination may be varied, it is desired herein to cover broadly the principle of moving a riffled surface and a stream of water in opposite directions to effect the separation of solids and the claim is directed to this end.

What I claim is:

Apparatus for separating solids having different specific gravities comprising a frame, a drum mounted for rotation about a horizontal axis on said frame, a plurality of corrugations extending longitudinally of the annular wall of said drum in substantially parallel relation to the axis of rotation thereof, said means forming riffles around the circumference of said drum, means for imparting rotary motion to said drum, water supplying means delivering a stream of water to the riffles at the top of the drum, said supplying means being arranged to cause the water delivered to the drum to move thereover in a direction opposed to the direction of rotation of said drum, means for delivering screened solids to the upper portion of said drum adjacent to the point of application of said stream of water, means for collecting and conducting moisture and waste away from said drum, sediment collecting means positioned below said drum, scraper means yieldably engaged with said riffles to cause sediment retained thereon to be deposited in said collecting means, and means for vibrating said drum during rotation thereof.

HENRY G. MARTIN.
